WIND-ORIENTED FEEDER RECEPTACLE

Carl E. Fenton, Box 124, Rte. 1, Arcadia, Fla.

Filed Mar. 5, 1963, Ser. No. 73,826

Term of patent 14 years

(Cl. D12—2)

FIG. 1.

FIG. 2.

FIGURE 1 is a front perspective view of a wind-oriented feeder receptacle showing my new design;

FIGURE 2 is a rear perspective view thereof;

FIGURE 3 is a medial, vertical, detail cross-section thereof, FIGURE 3 being taken substantially on the vertical plane of line 3-3 of FIGURE 2, looking in the direction of the arrows;

FIGURE 4 is a bottom plan view thereof; and

FIGURE 5 is a detail vertical, cross-sectional view thereof, FIGURE 5 being taken substantially on the vertical plane of line 5-5 of FIGURE 3, looking in the direction of the arrows.

I claim:

The ornamental design for a wind-oriented feeder receptacle, as shown.
